US0D1028608S

(12) **United States Design Patent** (10) **Patent No.:** **US D1,028,608 S**
(45) **Date of Patent:** **** May 28, 2024**

(54) **BAKEWARE**

(71) Applicant: **Hangzhou Keelife Network Technology Co., LTD**, Hangzhou (CN)

(72) Inventor: **Zhibin Peng**, Hangzhou (CN)

(73) Assignee: **Hangzhou Keelife Network Technology Co., LTD**, Hangzhou (CN)

(**) Term: **15 Years**

(21) Appl. No.: **29/855,928**

(22) Filed: **Oct. 8, 2022**

(51) **LOC (14) Cl.** **07-02**

(52) **U.S. Cl.**

USPC **D7/359**; D7/354; D7/360; D7/409

(57) **CLAIM**

The ornamental design for a bakeware, as shown and described.

DESCRIPTION

FIG. 1 is a front, left and top perspective view of a bakeware, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a view of FIG. 1 in the folded configuration thereof;

FIG. 10 is a view of FIG. 2 in the folded configuration thereof;

FIG. 11 is a view of FIG. 3 in the folded configuration thereof;

FIG. 12 is a view of FIG. 4 in the folded configuration thereof;

FIG. 13 is a view of FIG. 5 in the folded configuration thereof;

FIG. 14 is a view of FIG. 6 in the folded configuration thereof;

FIG. 15 is a view of FIG. 7 in the folded configuration thereof; and,

FIG. 16 is a view of FIG. 8 in the folded configuration thereof.
